ATTORNEYS

UNITED STATES PATENT OFFICE.

JOSEPH H. RUSBY, OF NUTLEY, NEW JERSEY.

ELECTRIC SWITCH.

1,290,362.

Specification of Letters Patent. Patented Jan. 7, 1919.

Application filed June 13, 1917. Serial No. 174,446.

To all whom it may concern:

Be it known that JOSEPH H. RUSBY, a citizen of the United States, residing at Nutley, in the county of Essex and State of New Jersey, have invented new and useful Improvements in Electric Switches, of which the following is a specification.

This invention relates to that class of electric switches in which a pair of spring controlled push buttons are operated to snap the blades into engagement or out of contact with the conductor devices to close or open the circuit.

The invention is designed to comprehend simple and efficient means coacting with a longitudinally slotted hinged lug for universally adjusting a switch relative to a wall.

The invention further provides the devices for making and breaking the current with a strongly braced frame, and a blade carrier of peculiar shape connected to the frame so that when operating the switch none of these actuating parts will accidentally break down or get out of order.

Another object of the invention is, to provide means for securing the blades to a carrier so as to prevent any short circuiting and to give positive engagement with the contact devices.

The other objects of the invention are more fully described in the following specification and claims and illustrated in the accompanying drawing in which:

Figure 1 represents a front elevation of a switch embodying this invention.

Fig. 2 is a longitudinal section taken along the line $\alpha\alpha$ of the same.

Fig. 3 is a vertical transverse section taken along the line yy of the same.

Fig. 4 is a front view of a blade carrier.

Fig. 5 is a plan or top view of the same.

Fig. 6 is a plan or top view of a frame and latch.

Fig. 7 is a side view of the same.

Fig. 8 is a side view of a rock lever, the blades having been removed.

Fig. 9 is a similar view looking at the opposite side of the device.

Fig. 10 is a detailed section of a barrel on a larger scale.

Fig. 11 is a detailed section of a blade mounting.

Figs. 12, 13, 14 and 15 are perspective views of the frame, blade carrier, rock lever and latch respectively.

In this drawing the letter a designates a block which can be made of any good insulating substance preferably such as porcelain. The block is equipped with a chamber b having a front wall c the object of these parts will be hereinafter described. A strap d is secured at e to the face of the block. The strap and the block have holes near each end for the insertion of a post or bolt f and a longitudinally slotted lug g is connected by means of the said post to the end of the strap, as denoted in Figs. 1 and 2. Tapped holes h located in the end of the strap, one being opposite the other are for engagement with ordinary cover securing screws not shown. The posts are connected at their rear ends to an armoring shell i made to cover the rear of the chamber and extend partly up the sides of the block. The posts when in place will hold the shell to the block and thus prevent it from slipping backward.

A device for securing and adjusting the block relative to the wall consists of a threaded stem j having a head k with a circumferential groove m best seen in Fig. 2. The grooved annular portion of the head of the screw engages the lateral walls of the longitudinal slot in the lug g and the threaded stem coacts with the wall devices not shown. This construction of the screw will permit vertical as well as to and fro adjustment of the switch block. Furthermore, the lug g by being swingingly connected to the strap as described will when the adjusting screw is actuated permit the block to be laterally adjusted or properly aligned with the opening in the wall.

On the face of the block are located a series of conductor devices n with contact blades o suspended from the conductors into the said chamber b of the block. These devices constitute the leads and terminals of an electric circuit.

The make and break mechanism to snap into engagement with the conductor blades includes a frame p with a forward portion q having holes for coaction with a pair of screws r for fastening the frame to the front of the wall c of the chamber. A hollow stud or sleeve s projects from one side of the frame, and it is fastened to the frame by riveting one end of it to the frame as indicated in Fig. 3.

A barrel t of practically large diameter is mounted to oscillate on the said hollow stud.

This barrel has a head *u* at one end formed by bending the sides of the barrel and an open opposite end. A rock lever *v* is secured by riveting tongues 12 forming projections from the periphery to the open end of the barrel. The rock lever has an upper portion bent at right angles to its body to coact with the shanks of a coiled spring 13 arranged on the barrel. A pair of push buttons 14 for actuating the rock lever are pivoted at 15 to the lever. At the head of the barrel is fastened a disk *t'* to confine the spring.

A blade carrier has arms 16 and 16', to straddle the barrel and for swinging connection with the frame. The fastening for the disk *t'* includes a pin 17 extending inwardly through the head of the barrel, the end 18 thereof being reduced for riveting the disk to the head. The pin also has a shoulder portion 19 and a pivot end 20, the function of the latter element will be herein-after described. The arms 16 and 16' of the blade carrier are parallel to each other and they are joined together by a contiguous front member 21 disposed at right angles to the arms. This member has a rearward bend parallel to the arms and a yoke member 22 joins the front member to the arm 16'. This construction permits the carrier to be shaped from a single sheet of steel and at the same time by its peculiar shape it forms a recess to give room for a latching device. The yoke member also limits the movement of the carrier by engaging one or the other side of the cut out portion of the frame. The arm 16' has lateral lugs 23 for coaction with a latching member 24 described below.

This latching device consists of a link 24 mounted on the pivot 20 projecting from the barrel. This link has a lug 25 sliding in a slot 26 located in the forward portion of the frame. The latch is pivoted approximately on a line with the pivots 15 near the fulcrum of the rocking lever *v* so that when the lever is operated the latch will move in a practically rectilinear line with the slot.

A pin 27 is carried by the hollow stud *s* and the ends of this pin strike against the walls of the chamber to obviate longitudinal movement. The pin projects beyond the frame on one side and its stud on the other so that it will serve for mounting a pair of blades 28 each being made of two sections of thin copper. The blades are insulated from the remainder of the mechanism by strips of mica 29 located between two metal strips 30 best seen in Fig. 11. The lower portions of these elements are fastened together by means of an eyelet 31 also employed for mounting the blades onto the pin. The opposite ends of the blade elements are fastened together by a bolt 32 riveted to the outer strip. The bolt and the eyelet have heads 33 fitted into apertures 34 in the arms

of the blade carrier. This method of movably mounting the blades to the carrier makes a durable structure giving positive alinement of the blades with the contacts and prevents short circuiting of the current. 70

When it is desired to operate the switch to close the circuit the upper button is pushed downward to rock the lever *v* and torsion or wind the coiled spring. The lug 25 of the latch has in the interval moved upward in 75 the slot 26 hence when the lever *v* reaches the end of its stroke, the lug 25 has moved beyond the lugs 23 on the carrier thus releasing the blades which by the tension of the spring snap into engagement with the 80 conductors *o* to close the circuit.

I claim:—

1. An electric switch comprising a longitudinally slotted hinged lug, and an adjusting screw made to engage a support seated 85 in the slot, said screw having an enlargement above and below the slot.

2. An electric switch comprising an insulating block provided with a strap, a slotted lug member swingingly connected to the 90 strap for laterally adjusting the block, and a screw made to engage a support having a grooved head for engagement with the slot to vertically adjust the block.

3. An electric switch comprising an insulating block provided with a strap, a longitudinally slotted lug member swingingly connected to the strap for laterally adjusting the block, a screw made to engage a support having an annular circumferential 100 groove for engagement with the slot for vertical and to and fro adjustment of the block.

4. An electric switch comprising a frame, a hollow stud fixed to the frame, a pin rotatively inserted in the stud with an end projecting beyond the stud, a blade carrier provided with an eyelet and mounted thereby on said end, said blade carrier being further provided with an aperture, a bolt head secured in the aperture, a switch blade mounted on the eyelet and the bolt, insulating material arranged on both sides of the blade, and a metal strip disposed on each outer side of the insulating material; the blade carrier, switch blade, insulating material and metal strips being made secure by said eyelet and bolt. 110

5. An electric switch comprising a vertical supporting frame, a stud fixed at a right angle on the frame, a rock lever mounted 120 concentrically upon the stud, a tubular spring mounting member open at one end for fastening the rock lever the other end having a hole for mounting upon the stud, and a projecting rim secured on the closed end of the tubular member to retain the spring in place on the tubular member.

6. An electric switch comprising a frame provided with a pin, a latch slidingly coacting with the frame, a blade carrier having 130

- parallel arms for mounting it on the pin, the arms being provided with a contiguous member to clear the latch and provide stops to limit the movement of the carrier.
- 5 7. An electric switch comprising a frame provided with a pin, a spring controlled barrel carried by the pin, means for oscillating the barrel, a latch pivoted to the barrel for sliding coaction with the frame, a
- 10 blade carrier having parallel arms for mounting it on the pin, the arms including a contiguous yoke member bent to form a recess for clearing the latch and to provide stops to engage the frame to limit the move-
- 15 ment of the carrier.

8. An electric switch comprising a frame provided with a pin, a spring controlled

mounting member carried by the pin, means for oscillating the member, a latch pivoted to the member for sliding coaction with the frame, a blade carrier having parallel arms for mounting it on the pin, the arms including a contiguous yoke member bent to form a recess for clearing the latch and to provide stops to engage the frame to limit the movement of the carrier.

In testimony whereof I have hereunto set my hand in the presence of two subscribing witnesses.

JOSEPH H. RUSBY.
